US0D1076158S

(12) United States Design Patent (10) Patent No.: US D1,076,158 S
(45) Date of Patent: * May 20, 2025

(54) MOTORCYCLE LIGHTING UNIT

(71) Applicant: Harley-Davidson Motor Company, Inc., Milwaukee, WI (US)

(72) Inventors: Rick Elchert, Mequon, WI (US); Brad Richards, Galisteo, NM (US); Bjorn Shuster, Hartford, WI (US); Dais Nagao, Menomonee Falls, WI (US)

(73) Assignee: Harley-Davidson Motor Company, Inc., Milwaukee, WI (US)

() Term: 15 Years

(21) Appl. No.: 29/879,558

(22) Filed: Jul. 10, 2023

Related U.S. Application Data

(63) Continuation of application No. 29/890,594, filed on Apr. 25, 2023, now Pat. No. Des. 1,059,220.

(51) LOC (15) Cl. 26-06

(57) CLAIM

The ornamental design for a motorcycle lighting unit as shown and described.

DESCRIPTION

FIG. 1 is a front and left side perspective view of a motorcycle lighting unit showing our new design, within the environment of a motorcycle;

FIG. 2 is a detail front and left side perspective view thereof;

FIG. 3 is a front and right side perspective view thereof;

FIG. 4 is a right side elevation view thereof;

FIG. 5 is a left side elevation view thereof;

FIG. 6 is a front elevation view thereof;

FIG. 7 is a rear elevation view thereof;

FIG. 8 is a top plan view thereof; and,

FIG. 9 is a bottom plan view thereof.

The broken lines are included for the purpose of showing portions of the motorcycle lighting unit and surrounding environment that form no part of the claimed design.

1 Claim, 9 Drawing Sheets
